BUS STOP SHELTER

Peter R. Hollaender, 2206 Raeburn Drive,
Cincinnati, Ohio

Filed Sept. 4, 1962, Ser. No. 71,537

Term of patent 14 years

(Cl. D13—1)

FIGURE 1 is a perspective view illustrating the rear of a bus stop shelter incorporating my new design.

FIGURE 2 is a front elevational view thereof.

FIGURE 3 is an end elevational view thereof.

FIGURE 4 is a cross sectional view thereof taken on the line 4-4 of FIGURE 2.

FIGURE 5 is a fragmentary cross-sectional view taken on the vertical plane through one of the panel sections at the rear of the bus stop shelter.

I claim:

The ornamental design for a bus stop shelter, substantially as shown.
